RADIO APPARATUS.

Application filed May 23, 1921. Serial No. 471,634.

This invention relates to an improvement in radio transmitting apparatus.

The object of the invention is to provide an apparatus of this kind which will be very compact, of simple construction, and highly efficient.

The invention consists in the features of construction, proportions of the coils and combinations of elements as will be more fully described in connection with the accompanying drawings and then particularly pointed out.

In the accompanying drawings,

Fig. 1 represents diagrammatically an arrangement of circuits embodying the principles of the invention;

Fig. 2 is a front view of transmitter apparatus embodying the invention;

Fig. 3 is a plan view of the apparatus shown in Fig. 2;

Fig. 4 is an end view looking from the right in Fig. 3, the end panel of the casing being removed and parts being shown in section on the line 4-4 of Fig. 3;

Fig. 5 is a rear view in elevation of the front panel of the apparatus;

Figs. 6 and 7 are detailed sections on the line 6-6 and 7-7 of Fig. 3;

Figs. 8 and 9 are front and edge views, respectively, of the antenna variometer device and parts immediately associated therewith;

Fig. 10 is a fragmentary sectional view on an enlarged scale illustrating a detail of said variometer device;

Fig. 11 is a detail in horizontal section of a part of the mechanism for actuating the antenna variometer;

Fig. 12 is a diagram with table referred to hereinafter, and

Fig. 13 is a diagrammatic view of a modification of the invention.

Referring first more particularly to Fig. 1, M, G, designate a motor generator set delivering alternating current of suitable frequency to the primary P of a transformer having a secondary S. A condenser 20 is connected across the secondary S. One side of the condenser and transformer secondary is connected through spark gap 21 to a heli-

cal inductance coil 22 forming what I will call the primary coil; while the opposite side of the condenser and transformer secondary is adjustably connected through movable switch arm 23 to said primary 22, 55 said switch arm being arranged to move over contact devices 24, which are connected, respectively, by leads 25 to adjusting tap points 26 on said primary winding.

The antenna A is connected through lead 60 27 and a variometer device 28, 29, to a variable point 30 on a helical inductance coil 31 which in the present case is inductively related to coil 22 and co-operates therewith. Variable tapping points 32 on said coil 31 65 are connected by leads 33 to contact devices 34 over which is arranged to sweep movable switch arm 35, said arm being connected by conductor 36, 37, 38, and variometer device 39, 40 to a variable contact point 41 on the 70 primary coil 22. Connection of the antenna circuit to ground is completed through variable contact 42, lead 43, hot wire ammeter 44 and lead 45.

The two movable switch arms 23, 35, are 75 arranged to be simultaneously moved by common actuating means over their respective sets of contact devices 24, 34, to vary the operating wave length as may be desired. As here shown, the said switch arms 80 are coupled together for simultaneous movement by intermeshing segmental gears 46, 47. In order to avoid the undesirable effect of dead end turns in the secondary coil 31, the end of said coil adjacent the primary coil is 85 permanently connected by lead 33^a to end contact 34^a of the secondary series of contact devices, which in turn is connected through leads 37, 38, etc. to the primary 22.

As shown, the secondary inductance coil 90 31 is co-axial with the primary coil 22 and somewhat spaced therefrom though partly within inductive range thereof. It is evident therefore that the primary and secondary circuits of the system are inductively 95 coupled and at the same time conductively coupled. As will appear more fully herein- after, the relative dimensions of the primary and secondary coils, the spacing apart there- of, and the exact arrangement of the various 100

connections to said coils, are matters of great importance in attaining one of the important objects of the invention, namely, a transmitter construction of such character that 5 operation can be had at any one of a plurality of different wave lengths selectively without having to alter the mechanical coupling of the two circuits, that is to say, without shifting the position of the ground 10 connection or of the coupler connection 41 on the primary inductance coil and without altering the distance between the coils 22 and 31. Before going into a discussion of how this object may be attained in practice 15 and formulating a general controlling law, it will be desirable to describe a typical transmitter construction embodying the general circuit arrangements already described, and such a construction is here illustrated in 20 Figs. 2 to 11 inclusive.

Referring to these drawings, the essential parts of the apparatus are supported on a casing or framework comprising front panel 50, end panels 51 and 52 extending rearwardly at right angles therefrom, and intermediate panel 53 disposed between said end panels. Said panels are of non-conducting material, and are secured together rigidly by sets of rods 54 and 55 which are either composed of or covered with non-conducting material. The primary and secondary inductance coils 22 and 31 are composed of flat copper ribbon wound spirally, the coil 22 being supported within the circular series of rods 54, and the coil 31 being similarly supported within the circular series of rods 55. The primary coil tapping points 26 and secondary coil tapping points 32 are shown as 30 slidable clips engaging the proper turns of the primary and secondary coils, respectively. The said tapping points are connected by their respective leads 25 and 33 to the two sets of contact devices 24 and 34 which are in the form of contact studs 40 mounted on the transmitter casing or framework. The contact studs 24 are mounted on the front face of the front panel, while the secondary contact studs 34 are mounted on a supplemental panel 56 located a short distance to the rear of the front panel and extending parallel thereto between the panels 52 and 53. The switch arms 23 and 35 sweep over the respective sets of contact studs 24 and 34, switch arm 23 being 45 mounted in front of the panel on its rotatable controlling shaft 57; while switch arm 35 at the rear of the panel 50 is secured to a hub 58, rotatable in a bearing provided in the said panel 50. Said hub 58 carried secured 50 thereto the beforementioned gear segment 47 which meshes with a similar gear segment 46 fixedly secured to shaft 57. Accordingly, when shaft 57 is turned by means of its controlling knob 59, said switch arms 23, 35, 60 65 are simultaneously swung over their respec-

tively co-operating sets of contact studs, but in opposite directions, to make the proper connections to the primary and secondary inductance coils for operation at anyone of the different wave lengths for which the apparatus may be designed or set. In this instance, operation can be effected at any one of six different wave lengths, but obviously this number may be varied as desired.

The antenna variometer before referred to, comprises generally the rotatable shaft 28 extending axially within the secondary inductance coil 31 and journaled at its opposite ends in the casing panels 52, 53, as shown, and the double cross arm 29 supported on said shaft in a manner to be more fully hereinafter described. Said arm 29 is of non-conducting material and in this instance is of rectangular cross section, except at its journaled ends. On opposite sides shaft 28 carries strips 62 of metal which are metallically connected to the metal bearing pivot 63 in which said shaft 28 terminates at the end adjacent the antenna lead 27. The antenna lead 27 is connected to a binding post 64, said binding post 64 being connected to said pivot 63 by means of a wiping brush connection 65. The double cross arm 29 is so mounted on shaft 28 as to be compelled to rotate therewith but to be slidable longitudinally thereon. Said cross arm is of non-conducting material in this instance, and it carries at its opposite ends bifurcated metallic shoes or contact devices 66 and 67, each of which contact shoe fits over the inner edge of the copper ribbon conductor forming the secondary inductance coil. One of said contact shoe devices, 66 in this instance, is electrically connected by means of a metal strip 68 and brushes 69, with said metal strips 62; while the other contact shoe device 67 remains insulated from said strips and therefore serves in this case merely as a guide device. By rotating the shaft 28, the guide devices 66 and 67 follow the helical turns of the primary coil 31, the cross arm 29 being at the same time moved longitudinally along the shaft 28, the connection of the contact member 66 to the antenna through the sliding brush arrangement just described being continuously maintained. In this way, the portion of the secondary inductance coil actively in the antenna circuit may be adjusted as required.

The variometer device 39, 40 to which the secondary switch arm 35 is connected is similar in all essential respects to the variometer device 28, 29, just described, and its construction therefore does not require detailed explanation. The shaft 39 of the primary variometer device is journaled at one end in panel 51 and at the other end has a metal pivot 39 journaled in an auxiliary panel 70 which also serves to carry the ends of rods 54. The shaft 39 may be rotated to adjust 120 125 130

the primary or coupling variometer by means of the knob 71. Any adjustable means may be provided for rotating the shaft 28 of the antenna variometer. In this 5 instance said shaft carries a beveled gear 72 meshing with a beveled pinion 73, said pinion being fast on a shaft 74 which is supported by and extends through a fixed bushing or bearing sleeve 75 upon which the hollow 10 shaft 57 of the primary switch arm control is revolvably carried. The shaft 74 has an operating knob 76 secured to the outer end thereof and projecting slightly beyond the controlling knob 59, as shown.

15 The leads, 36, 37, and 38, connecting the secondary switch arm to the shaft 39 of the primary coupling variometer are clearly indicated in Figs. 3, 5 and 11. A spring washer 39^c insures good contact between metal 20 collar 39^b pinned to pivot 39^a and lead 38.

In case of extreme variations in the length of the antenna, either through accident or otherwise, it may be desirable to alter the 25 normal angular relation of the switch arms 23, 35 with respect to each other, in order to effect adjustments necessitated by such extreme variations. One way of providing for this is illustrated in Fig. 6, where the primary arm 23 has a hub 77 loose on a bushing 78 that is secured in any suitable manner to hollow shaft 57 (made of insulating material), for rotation therewith. Said arm 30 23 carries a latch 79 pivoted thereon, said latch being adapted to enter any one of several notches 80 provided in the cover plate 35 81. Leaf spring 82 engaging said latch member 79 tends to hold it either in the operative coupling position shown in Fig. 6, or to hold it in inoperative position when the 40 latch is turned up out of coupling position by lifting on the knob 83.

The spark gap 21 is of the quenched type, comprising a plurality of elementary spark gap units 84 supported in holder arms 85 45 on the lower part of panel 50, said gap units, when supported as shown being in end to end contact and therefore connected in series. As the construction of the spark gap forms no part of the present invention, detailed description thereof is deemed unnecessary. The 50 respective ends of the complete quenched gap are connected in the closed oscillation circuit by leads 86, 87, as shown.

The apparatus hereinbefore described contains a number of advantageous mechanical 55 features, but a particularly important feature is the relative dimensioning of the primary coil, the secondary coil, and their relation to each other. In Fig. 12 I have given 60 a diagram indicating the two coils as well as their measurements, and in connection with this diagram I have given a table setting forth the measurements of the various 65 dimensions indicated in the diagram, these measurements being stated in inches, in turns

of winding for the respective coils, and in ratios, to the diameter of the primary coil. The dimensions are taken from a completed apparatus which gave highly successful results working on an antenna having a capacity of .0005 microfarads. On this diagram, Fig. 12, G indicates the tapping point for the ground lead; t means turns; figures in a circle indicate ratio to the diameter of the primary coil, and figures with the double prime mark indicate inches. The table comprises two parts, the left hand table referring to the primary coil, while the right hand table refers to the secondary coil. Wave lengths are indicated by the Greek letter λ . 70 Turns of the primary are indicated by t_1 , and turns of the secondary are indicated by t_2 . The other headings for the lines will be obvious from the explanation hereinbefore given.

75 The point where the lead from the loading inductance or secondary coil is connected to the primary coil is indicated at H.

80 The end of the primary coil to which the primary circuit has the continuous connection, is indicated at Z.

85 The antenna connection with the secondary or loading coil is indicated at W, it being understood that the said secondary or loading inductance should be provided with 90 two extra turns outside this antenna connection.

95 Although in Fig. 12 I have given measurements in inches, in the subsequent discussion of methods and calculation I will employ the units of the metric system.

100 The distance measured on the primary coil in centimeters from the end Z (Fig. 12) to the point G will hereafter be known as g ; the corresponding distance from the end Z to the coupling connection H will hereafter be designated as h .

105 The length of the primary coil from the end Z to the point where the lead of highest wave length connects, and which in some 110 cases will be practically the total length of the primary coil, I will hereafter refer to as the length v .

115 In the design of an apparatus embodying the present invention, if the ratio of the capacity of the primary circuit to the capacity of the antenna circuit is substantially 8, that is, if

$$\frac{C_1}{C_2} = 8,$$

120

125 a new apparatus may be designed by first selecting a suitable diameter for the primary coil and then designing the other dimensions of the primary and secondary in accordance with the ratios given in the diagram, Fig. 12, and in the accompanying table. In practice, the ratio of these capacities is about of the value given for the one-half kilowatt and one kilowatt sets.

130

In order, however, to enable those skilled in the art to design apparatus embodying my invention for various conditions, I give the following explanations of the method of procedure:

One knows the capacity (C_1) of the primary circuit, the capacity (C_2) of the secondary circuit, the coupling, K , which it is desired to maintain, and the wave lengths at 10 which the apparatus is to work. With this information one proceeds as follows:

Find the value of

$$15 \quad K \sqrt{\frac{C_1}{C_2}}$$

With this value as the argument, enter the Table T_1 (given below) and take out the corresponding values g_o and h_o . If the exact argument does not appear in the first 20 column, the table may be interpolated in any suitable manner, as for example, by graphic methods, that is to say, by plotting the value of g_o as ordinates with the corresponding values of the argument

$$25 \quad K \sqrt{\frac{C_1}{C_2}}$$

as abscissæ, on a relatively large scale, drawing a smooth curve through the points for the given ordinates, and then with the particular argument, measuring the desired g_o . By the same graphic method the value of h_o for any argument may be determined 35 with sufficient accuracy for practical purposes.

With g_o as the argument enter the Table T_2 (given below), the value of g_o being found in the first column designated L_o . From this take out the corresponding value 40 in the column, L_o , which I will designate as L_{og} . Also with h_o as an argument enter the table T_2 and take out the corresponding value in the column L_o , which value I will 45 designate as L_{oh} .

Let λ_o indicate the lowest wave length of the various wave lengths given.

One now finds the value of the self inductance of that part of the coil extending from 50 that end where one primary lead is fixed to the point where the ground lead is to be connected. This value (L_o) is given by the following formula:

$$55 \quad L_o \text{ (microh.)} = \frac{1}{(1884)^2} \cdot \frac{\lambda_o^2}{C_1} \text{ (meters)}$$

The pitch, P_1 , of the primary winding is determined by the usual practice, and usually is about as stated in table Q set forth below, for the most generally used power values stated in the column marked KW. This table also gives the usual values of primary capacity, C_1 , secondary capacity, C_2 , and pitch, P_2 , of the secondary winding, or 65 loading inductance.

From the values L_{og} , L_o , and P , one proceeds to determine the diameter of the primary coil, by the following formula

$$70 \quad D = 3 \sqrt{\frac{P_1^2 L_o}{L_{og}}}$$

Next, one determines the distances, g and h of the ground and coupling leads from the end of the coil nearest it, thus

$$75 \quad g = g_o D \quad h = h_o D$$

Now one can determine the wave length λ_H of the coil at the above mentioned distance h

$$80 \quad \lambda_H = \lambda_o \sqrt{\frac{L_{og}}{L_o}}$$

This gives the essential dimensions of a primary coil with purely conductive coupling from wave length λ_o to the wave 85 length λ_H and if this range covers all the wave lengths required, the second coil may be a pure loading coil, that is, it may be placed out of inductive reach of the primary. The positions for the taps for the 90 desired wave lengths between λ_o and λ_H need not be calculated, because they may be found by tuning, it being understood that all the tapping leads have variable connections to the coil.

Where the wave length range is to be extended to higher values than λ_H determined as hereinbefore explained, it is necessary to resort to some inductance coupling between the primary and secondary circuits, and this is done by extending the length of the primary coil to a value v which will be most satisfactory if not much greater than $h + .5D$, and may be less if desired. Assuming it to be $h + mD$:

With the value of v determined and m selected, one next proceeds to find the wave length λ_v at the point v . First one finds a value v_o as follows:

$$110 \quad v_o = h_o + m$$

Entering table T_2 with v_o as an argument, one takes out the corresponding value in column L_o , which value I will designate L_{ov} .

Then one determines λ_v as follows:

$$115 \quad \lambda_v = \lambda_o \sqrt{\frac{L_{ov}}{L_{og}}}$$

This will give one the highest wave length of the primary coil. This will be, also, the highest wave length of the open circuit or antenna circuit.

One now proceeds to determine the dimensions of the coil for the open circuit or antenna circuit, to serve either as a loading coil, which, as before explained, will be the case where the desired range of wave length of the primary may be obtained in the length, h , or to serve as a combined secondary and loading coil in the case when the 125

primary coil was extended substantially beyond the length h to the length v and the open circuit coil is to be placed with some turns in inductive relation to the primary 5 coil, that is to say, is to have some turns acting as a secondary and the others as mere loading coils.

The total inductance L_2 of the antenna circuit is found as follows:

$$L_2 = \frac{\lambda_H^2}{(1884)^2 C_2}$$

The total inductance L_2 includes the inductance L_c of that part of the primary coil 15 included in the antenna circuit, as well as the inductance L_a of the antenna, and, of course, must include the inductance L_s of the open circuit coil. That is

$$L_2 = L_c + L_a + L_s$$

To calculate L_c we proceed as follows:

$$c_o = H_o - g_o$$

25 From table T_2 with c_o as the argument, one takes the corresponding value in column L_o , which value I will designate L_{oc}

$$L_o = L_{oc} \times \frac{L_G}{L_{oc}}$$

$$\text{Then } L_s = L_2 - L_c - L_o$$

The value of the inductance L_s being found, the coil is to be suitably proportioned. In practice, it is well for present 35 purposes to have the ratio of length to diameter about 1.5. Some departures from this ratio, which I will designate l_{os} , are permissible, but it is advisable not to depart too far.

40 With l_{os} as the argument one takes from the table T_2 the corresponding value in the column L_o which I will designate as L_{os} . The pitch of the secondary coil is determined by usual practice and will probably 45 be about as stated in table Q hereinbefore referred to. This selected pitch I will designate as P_2 . The diameter D_2 of the second or loading coil may now be determined, as follows:

$$D_2 = 3 \sqrt{P_2^2 \times \frac{L_s}{L_{os}}}$$

50 If the open circuit coil is a mere loading inductance, it is left out of substantial inductive relation to the primary.

If, however, the open circuit coil is to be used as a secondary to the primary, it must be properly adjusted in coaxial relation thereto in order to give a proper coupling.

60 To do this, adjust the two circuits in resonance at the longest wave length λ_v with the ground G and the coupling H at the calculated points; then move the secondary relative to the primary coil until the best coupling is obtained. Then secure the sec-

ondary coil in this position. The coupling will be automatically maintained at substantially the value for which the apparatus was designed, throughout all the wave lengths.

The taps for the secondary are determined 70 as explained for the primary coil.

While the coupling of the apparatus designed above is automatically maintained at substantially the calculated value, there may be a trifling variation from that employed 75 in the calculations at wave lengths other than those designated λ_G and λ_H , and inaccuracies of material and construction may sometimes introduce considerable deviations from the best coupling at various wave 80 lengths.

An important feature of my invention consists in means for compensating for these deviations, which comprises the inclusion when necessary of a condenser or an inductance in any one of the leads between the contact point of the quick-change switch and the variable connector for such lead. The condenser may be used in the primary circuit or in the secondary circuit. Individual condensers for correcting coupling are shown in the secondary circuit at w in Fig. 13. They are not subjected to high potentials and hence need not be expensive.

Instead of using individual condensers x 95 for correcting the coupling as above indicated, it is sometimes advantageous to employ individual inductances in the said leads, as indicated at y , Fig. 13.

In the practical construction of an apparatus for a definite situation, the secondary and loading coil may be fixed in place after its proper relation to the primary coil has been determined by test as hereinbefore explained. However, in order to provide apparatus of more flexibility, the combined secondary and loading coil may be mounted adjustably with relation to the primary coil in such a way that it will remain in any adjusted position.

75 It will be noted that in my construction the primary coil has a series of coupling turns between the points G and H (Fig. 12) and that the primary circuit always includes a number of turns in the direction of Z (Fig. 12) which I will designate as beyond the coupling turns. In other words, the coupling turns are never at the extreme end of the coil where the non-variable connection of the primary is made. This is an important features of my invention, and this construction, coupled with the proper designing of the coil, enables me to obtain the advantageous results of a practically constant coupling, throughout all the wave lengths.

The apparatus specifically shown and described is intended for transmission in connection with spark gaps, that is to say, for quenched spark gap operation. However, the primary coil, the loading inductance or

secondary coil, and their associated switching mechanism and adjusting devices may be employed in any transmitting system, whether employing arcs, tubes or generators, and, furthermore, may be used as the tuning apparatus in receiving sets, in which case, of course, the circuits and coils would be designated reversely from their present designations, that is to say, what is referred to hereinbefore as a primary circuit would be called a secondary circuit in a receiving apparatus, and vice versa. More generically, the circuits may be referred to as the open circuit and the closed circuit.

15 The tables referred to in the specification are as follows:

Table Q.

55 What I claim is:

1. In a radio apparatus, a closed circuit, an inductance coil inductively related to said circuit, a transformer coil connected nonvariably with said circuit at one end and having all its coupling turns away from that end of the coil at which the non-variable connection of the closed circuits is made and having the distances of the beginning and end respectively of the coupling turns from said end so proportioned with respect to the

turns of said inductance coil that a substantially uniform coupling will be maintained, substantially as described.

2. In a radio apparatus, the combination with an inductance coil having an antenna connection near one end and a transformer connection near the other end, of a transformer coil having its magnetic field arranged to envelop the magnetic field of said inductance coil and arranged to have one end connected to one end of a closed circuit, means for making a ground connection and a coupling connection for the transformer connection of said inductance coil, whereby a portion of the turns of the transformer serve as conductive coupling turns, all of said coupling turns being away from that end of the transformer coil to which the closed circuit is connected as aforesaid, a series of contacts for the transformer coil, a series of individual leads running from said contacts to tapping points on the transformer coil, a series of contacts for said inductance coil, a series of individual leads running from the latter contacts to tapping points on the said inductance, means for making a connection from the conductive connection of the transformer coil to any desired contact point of said inductance, and means for making a connection from the closed circuit to any one of the contact points of the transformer coil. 95

3. In a radio apparatus, the combination with an inductance coil having an antenna connection near one end and a transformer connection near its other end, of a transformer coil arranged to have one end connected to one end of a closed circuit, means for making a ground connection and a coupling connection for the transformer connection of said inductance coil, whereby a portion of the turns of the transformer serve as conductive coupling turns, all of said coupling turns being away from that end of the transformer coil to which the closed circuit is connected as aforesaid, a series of contacts for the transformer coil, a series of individual leads running from said contacts to tapping points on the transformer coil, a series of contacts for said inductance coil, a series of individual leads running from the latter contacts to tapping points on the said inductance, a pair of switching means for making a connection from the conductive connection of the transformer coil to any desired contact point of said inductance, means for making a connection from the closed circuit to any one of the contact points of the transformer coil, and mechanism interconnecting said switching means for operating both said switching means simultaneously whereby movement of one switching means imparts movement to the other switching means. 115

4. In a radio apparatus, the combination with an inductance coil having an antenna

- connection near one end and a transformer connection near its other end, of a transformer coil arranged to have one end connected to one end of a closed circuit, means 5 for making a ground connection and a coupling connection for the transformer connection of said inductance coil, whereby a portion of the turns of the transformer serve as conductive coupling turns, 10 all of said coupling turns being away from that end of the transformer coil to which the closed circuit is connected as aforesaid, a series of contacts for the transformer coil, a series of individual leads running 15 from said contacts to tapping points on the transformer coil, a series of contacts for said inductance coil, a series of individual leads running from the latter contacts to tapping points on the said inductance, a plurality of 20 switching means for making a connection from the conductive connection of the transformer coil to any desired contact point of said inductance, means for making a connection from the closed circuit to any one of 25 the contact points of the transformer coil, and mechanism for operating said switching means separately and simultaneously whereby movement of one of said switching means imparts movement to the other of said 30 switching means.
5. In a radio apparatus, the combination with an inductance coil having an antenna connection near one end and a transformer connection near the other end, of a transformer coil arranged to have one end connected to one end of a closed circuit, means 35 for making a ground connection and a coupling connection for the transformer connection of said inductance coil, whereby a portion 40 of the turns of the transformer serve as conductive coupling turns, all of said coupling turns being away from that end of the transformer coil to which the closed circuit is connected as aforesaid, the distances of the 45 beginning and end of the said coupling turns from said end being so proportioned that a suitable coupling will be maintained, a series of contacts for the transformer coil, a series of individual leads running from 50 said contacts to tapping points on the transformer coil, a series of contacts for said inductance coil, a series of individual leads running from the latter contacts to tapping points on the said inductance, variable 55 means for making a connection from the conductive connection of the transformer coil to any desired contact point of said inductance, and variable means for making a connection from the closed circuit to any one 60 of the contact points of the transformer coil, said variable means being simultaneously adjustable whereby adjustment of one of said means effects corresponding adjustment of the other of said means.
6. In a radio apparatus, the combination 65 with a coil proportioned to determine various suitable wave lengths, a separate coil arranged to act inductively on said first mentioned coil, a series of contact devices, leads from each contact device to a corresponding 70 tapping point on the first mentioned coil, each lead having a variable connection to said first mentioned coil, an individual coupling-correcting, impedance device arranged in one or more of the leads, and 75 switch mechanism for making the proper circuit connection to any desired contact device.
7. In a radio apparatus, the combination of a pair of coils inductively and conductively connected together, means for energizing one of said coils, a ground connection for the coil to be energized, means for varying the number of turns of said coil to be connected with the energizing means, means for varying the number of turns of the other coil to be conductively connected to the coil to be energized, and means for varying the number of turns of the two coils being in engagement to move in unison, and 80 an antenna connection for the other coil.
8. In a radio apparatus, the combination of a pair of coils placed end to end and both inductively and conductively connected, a circuit containing means for energizing one of said coils, one end of said circuit being 85 connected to the coil to be energized at a point remote from the other coil, means for varying the number of turns of the coil to be energized and connected to said circuit, a ground conductor connected to the coil to be energized at a point remote from the other coil, means for varying the number of turns of the other coil to be conductively connected to the coil to be energized, and an antenna connection for the other coil, the means for 90 varying the number of turns of the two coils being joined so as to operate in unison.
9. A high frequency signaling apparatus comprising in combination a pair of inductance coils axially aligned and connected inductively and conductively, a circuit for energizing one of said coils, said circuit being connected to the coil to be energized at a point remote from the other coil, means for including a variable number of turns of 95 said coil to be energized in said circuit, a connection to the other of said coils with a radiating system, means for varying the effective number of turns included in circuit with said radiating system, each of said 100 means being simultaneously operative in such manner that motion of one of said means imparts corresponding motion to the other of said means.
10. A high frequency signaling apparatus comprising in combination an oscillatory circuit, a radiating circuit, a pair of inductances each fixed in spacial relation with respect to each other and inductively and conductively associated, connections between 105 110 115 120 125 130

- one of said inductances and said oscillatory circuits, connections between the other of said inductances and said radiating circuit, and means simultaneously operative for adjusting the effective number of turns of said inductances included in the respective circuits, the movement of one of said means serving to impart corresponding movement to another of said means for effecting the tuning of said circuits and adjusting the coupling thereof without change in the spacial relation of said inductances.
11. A high frequency signaling apparatus comprising in combination an oscillatory circuit, a radiating circuit, a pair of inductances each fixed in spacial relation with respect to each other and inductively and conductively associated, connections between one of said inductances and said oscillatory circuit, connections between the other of said inductances and said radiating circuit, a pair of separate switching devices for varying the effective number of turns of said inductances included in said oscillatory circuit and said radiating circuit respectively, said switching devices being geared together in such manner that movement of one of said switching devices operates to impart simultaneous movement to the other of said switching devices for controlling the coupling between said inductances without varying the spacial relation thereof.
12. A signal transmitting apparatus comprising in combination a high frequency oscillatory circuit, a radiating circuit, a pair of independent inductance coils each axially aligned end to end arranged one in the magnetic field of the other, a connection between said inductance coils, connections between one of said inductance coils and said oscillatory circuit, connections between the other of said inductance coils and said radiating circuit, and switching means for each of said inductance coils for controlling the effective number of turns thereof in said circuits and a mechanical actuator extending between said switching means for effecting simultaneous movement thereof whereby the movement of one of said switching means operates to produce a corresponding movement of the other of said switching means for variably controlling the coupling between said circuits without change in the spacial relation of said inductance coils.

FRITZ LOWENSTEIN.
